APPARATUS FOR TREATMENT OF WEBS
Karl F. Cossaboon, Claymont, Del., assignor to E. I. du
Pont de Nemours and Company, Wilmington, Del., a
corporation of Delaware

Filed Sept. 9, 1959, Ser. No. 838,989
19 Claims. (Cl. 118—41)

This invention relates to a completely integrated automatic apparatus for unwinding webs from rolls, splicing the successive strips, treating the webs, rewinding the treated webs into rolls and removing the latter all under controlled conditions. The invention also relates to an automatic roll changing unwind unit for supplying webs to such an apparatus and removing the cores under controlled vacuum conditions. It also relates to an automatic roll handling unit for applying treated web to cores and removing wound rolls of web from such an apparatus under controlled vacuum conditions. The invention also is concerned with such a unit which has means for rewinding the web with either desired surface outermost on the rewound rolls. Still more particularly the invention relates to an integrated apparatus in which the web supplying unit and the web rewinding and removing unit are operated in synchronism through an electronic web footage counter, and means for controlling, severing and splicing the web are provided.

Various types of machines are known for supplying rolls of webs to be treated as a continuous strip. However, they do not lend themselves readily to a continuous operation wherein a coating operation is continuously carried out under conditions of highly reduced pressure. Also, they generally have an accumulator chamber to store the web while splicing so that there will be no interference with the treating or other operation.

An object of this invention is to provide a practical and dependable apparatus for continuously treating a web, especially under reduced pressure conditions, while continuously supplying separate rolls of web and removing the cores, and while rewinding the treated web onto separately supplied cores and removing the rewound rolls. Another object is to provide such an apparatus which can be maintained under reduced pressure and lightproofed conditions over long periods of time. Yet another object is to provide such an apparatus which can be operated at high rates of speed and still permit web severing and splicing to be carried out without changing the speed of the web or the provision of web-accumulation devices and chambers.

A further object of the invention is to provide such an apparatus which is compact and can be carefully controlled to permit web severing and splicing operations and rewind operations with either surface outermost in the rolls of treated web. A still further object is to provide such an apparatus which enables the coating of the web to be carried out at a high degree of vacuum without the necessity of squeeze rolls or other constructions to bear against the web and maintain the reduced pressure. Still other objects of the invention will be apparent to those skilled in the art from the following description of the invention.

The novel apparatus of this invention will now be described with reference to the attached drawings which constitute a part of this application and in which like parts are given the same reference numerals throughout the several views or figures.

FIGURE 1 is an elevation of the entire automatic apparatus for unwinding, splicing, coating, rewinding webs;

FIGURE 12 is a plan view (with parts in section) of the rewind unit taken along the lines 12—12 of FIGURE 9;

FIGURE 13 is a detailed vertical sectional view of the door to the inner chamber (rewind unit);

FIGURE 14 is an elevation of the detail of cylinder and lever mechanism for the door of FIGURE 13;

FIGURE 15 is an end elevation of the door, closure cylinder and mechanism for the inner vacuum chamber (unwind unit);

FIGURE 16 is a detailed vertical sectional view taken along the lines 16—16 of the door of FIGURE 15 to the inner chamber (unwind unit);

FIGURE 17 is a side elevation of the operating cylinder, rack and gear segment which operates the roll-transfer arms for the unwind unit;

FIGURE 18 is a detailed elevation of the web-severing knife for the unwind unit;

FIGURE 19 is a plan view showing details of one end of the web-severing knife, lever and pivots for the unwind unit;

FIGURE 20 is a perspective view of a roll of web with a double pressure-sensitive tape attached to one end;

FIGURE 21 is an enlarged side elevation of a safety-lock mechanism to hold the splicing roll in position during web severing;

FIGURE 22 is an enlarged plan of the mechanism of FIGURE 21;

FIGURE 23 is an enlarged side view of a device for measuring the diameter of a new roll of web;

FIGURE 24 is an enlarged plan view of the device of FIGURE 23;

FIGURE 25 is an enlarged side view of a web-aligning device;

FIGURE 26 is an enlarged plan view of the web-aligning device of FIGURE 25;

FIGURE 27 is an enlarged side elevation of wrap roll and web-severing knife for the rewind unit;

FIGURE 28 is a left-end elevation of the mechanism of FIGURE 27;

FIGURE 29 is an enlarged section of the plunger housing.

FIGURE 30 is a side elevation showing the operating cylinder, rack and gear mechanism for indexing the wrap rolls;

FIGURE 31 is a right-end elevation of the cylinder rack end connection of the mechanism of FIGURE 30;

FIGURE 32 (sheet 1) is a schematic flow chart showing the relationship of the tachometers, pulse generators, and general electrical circuits for operating the splicing

and cutting mechanisms for the unwind unit and rewind unit;

FIGURE 33 is a detailed perspective view showing the tachometers connected to the web roll core and web idler roller.

Referring now to FIGURE 1 of the drawing, the entire apparatus is shown in elevation in outline and in a practical arrangement where the web rewind unit is placed over the web unwind unit. This is merely a preferred and not a necessary arrangement of the various units.

With reference to FIGURE 1 of the drawing, the apparatus comprises an unwind unit A, an elongated housing B connecting the unwind unit with a coating and drying unit C, and an elongated housing D connecting the latter to rewind unit E.

The Unwind Unit

The unwind unit A, while shown in outline in FIGURE 1, is shown in greater detail in FIGURES 2, 3, 4 and 5. It comprises an enclosed central vacuum chamber 50, the casing of which has end walls 51 and 52 provided with door openings 53 and 54 which are closed by means of sealing doors 55 and 56, respectively. These doors, as shown in greater detail in FIGURES 15 and 16, have a central lug 57 protruding from their outer surfaces. A horizontal pin 58 passes through each lug and through the ends of spaced vertical levers 59 having their upper ends provided with a lug 60 which is attached to a shaft 61 which, in turn, is fastened to a link 62 having on one end pintle 63. The clevis end 64 of piston rod 65 interfits with this pintle and the other end is attached to a suitable piston (not shown) in fluid pressure activated cylinder 66 which has its lower end pivotally attached to a pintle 67 on a bracket 68 attached to the wall of chamber 50.

Openings 53 and 54 in the end walls of the central chamber connect with an enclosed vacuum interlock web roll receiving chamber 69 and with a vacuum interlock core removing chamber 70. These chambers have door openings 71 and 72 in their outer respective end walls. The latter are provided with pivoted sealing doors 73 and 74, respectively. These doors, as more clearly shown in FIGURE 4 and FIGURE 8, have a central lug 75 protruding outwardly from the outer surface. A pin 76 extends through this lug and through Y-shaped yoke 77 having radial arms 78 and 79 and lateral arms 80 and 81 through which passes vertical shaft 82 journaled in suitable bearings 83 and 84 which bearings are fastened by means of bolts 85 to the end wall of the respective outer chambers. The other arm of the Y-shaped yoke 77 has a slot 86 which engages the end of bolt 87 pivoted at one end on a bracket 88 fastened to the end wall adjacent the edge of the door. This bolt is threadably engaged with a handle 89 that extends across the slot. The doors have a flat portion which overlaps the flat surface of the walls adjacent the door openings. If desired, suitable gaskets such as tubes, O rings, strips of resilient material, e.g., rubber or other material, can be fitted into grooves on the doors in order to form a more perfect seal.

Web roll receiving chamber 69 is provided with an opening 90 which is connected to a suitable vacuum pump. This chamber is provided with U-shaped arms 91 having their upper inner ends journalled on a shaft 92 mounted on suitable bearings attached to the frame of the apparatus in any practical manner. As shown in FIGURE 17, the outer end of this shaft has keyed thereto a crescent-shaped gear 93 which meshes with rack 94 attached to clevis 95 on the end of piston rod 96 which is in turn connected to a piston (not shown) in the roll transfer fluid pressure-actuated cylinder 97. The latter is attached to the frame for the apparatus in any suitable manner and is provided with operated valves, controls and connections to a suitable source of fluid pressure.

A seal can be provided on shaft 92 at the point where the shaft emerges from the casing. Suitable seals are well known and to eliminate unnecessary detail, a par-

ticular seal is not shown here. Similar seals can be used with all rotating shafts which extend through the casing. The "Duraseal" Model RA, rotary, No. 55 facing No. 14 carbon bushing in O rings, manufactured by Durametallic Corp., Kalamazoo, Michigan, can be used.

The outer ends of the U-shaped levers 91 are notched and thus adapted to receive the ends of mandrel 98 of the core 99 of the roll of web W. A fluid pressure-actuated cylinder 100 is pivotally mounted by means of pivot pins 101 attached to the lower end of each U-shaped arm. The piston rod 102 from this cylinder has a clevis end which is connected to a suitable pintle 103 on pivoted latch 104. This latch 104 is pivotally mounted on pintle 105 on the U-shaped arm. The latch extends around the end of the core shaft and holds it in the curved notch during a web transfer action.

The web roll cores have cylindrical flanges 106 mounted on the recessed outer ends of mandrel 98. One of the pair of cylindrical flanges on said mandrel is provided with an interfitting U-shaped or channeled annular ring 107 which consists of two L-shaped rings held together near their peripheries by suitable screws or bolts (not shown). The annular ring is adapted for rotation as a rim about the interfitting flange. The ring can be adjusted and locked in any angular position by means of a threadably engaged thumb screw 108 having an enlarged head 109 and a shank, the end of which shank extends into an annular groove 110 in a side wall of the flange 106. In the periphery of the annular ring is a small permanent magnet insert 111 which coacts with suitable electrical pickups 112 mounted on the side wall (140 of the sheath frame), as shown in FIGURES 2 and 3. The magnetic insert and pickup sense the passage of the permanent magnet insert at the time splices are accomplished. In so accomplishing splices between an expiring web roll and the leading end of a new web roll, it is essential that the splicing mechanism be actuated when it is sensed that the leading end of a new web roll is in a preselected angular (or circumferential distance) relationship with the machine elements.

The flanges have tapered ends 113 which interfit with the recess 114 in the end of an interfitting chuck 115. This is shown more fully in FIGURES 5 and 5A of the drawing.

The flanges on the cores also have a spring-pressed

detent 116 which locks into a hole 117 on the chuck which will be further explained below.

Web roll receiving chamber 69 is also provided with a device for measuring the diameter of a new web roll. This device consists of a roller 118 rotatably mounted in a clevis 119 which is secured to the end of cylindrical shank 120 in the upper side of which is machined a series of gear teeth 121 forming a rack. The rack-shank is slidably engaged, in a near-horizontal position, in two ball bushings 122 which are mounted to a first vertical wall 123 of a bracket 124 which has a second vertical wall 125, at right angles to the first, having a rear face 126 which mounts against the side of the end wall 51 which is in the receiving chamber 69 (see FIGURE 2); the bracket 124 is located centrally between the pair of U-shaped arms 91. The measuring device is thus mounted such that the axis of the cylindrical shank 120 is disposed radially in respect to a newly introduced web roll W.

The rack-shank is urged radially toward the web roll axis by a spring 127, thus the roller 118 will lie against the periphery of the web roll and the position of the shank will be a measure of the web roll diameter. The device is further provided with a pinion 128, in driving engagement with the rack; the shaft 129 for this pinion is journaled in bearings 130 which are secured to the first vertical wall of bracket 124. At the far end of shaft 129 and coupled therewith is the rotor shaft 131 of a rotary switch 132; the stator of the switch is secured to the bracket 124. The switch rotor (not shown) is continuously rotatable, having a single contact blade on the rotor adapted, upon being rotated, to make successive electrical contact with each of a plurality (e.g., 40) of

stationary contact members (not shown) in the stator. The position of the switch rotor then will be established when a new web roll is placed in the U-shaped arms 91 and the rotor position will be a measure of web roll diameter.

Central vacuum chamber 50, as will be apparent from the drawings, embodies a casing with welded side walls, end walls and a bottom plate 133. It also has a top plate 134 provided with an opening 135 for passage of a web W. This plate can be welded, bolted or otherwise firmly attached to the side and end walls. The end walls have welded thereto four heavy brackets 136 which are welded to or otherwise affixed to a heavy welded inner sheath frame 137. This frame has two end walls 138 which are spaced a short distance from the inner end walls of the chamber. The upper part of these walls is also firmly attached to the inner walls of the casing or chamber. Between the end walls of the inner sheath are two side walls 139 and 140. The central part of these side walls has a depending trapezoidal central segment. This sheath frame serves as a support for the various drive shafts and pivoted yoke of the web and roll handling mechanism.

Journalled in a suitable welded collar 141 in the central lower part of the trapezoidal segment of each side wall of the sheath is a large stubshaft 142 on which is journalled bearing block 143 constituting the central part of yoke 144. This yoke has an upper and a lower arm between the ends of which are bearing blocks 145. As shown in FIGURE 5, this block has a pair of antifriction bearings 146 which engage the bearing surface of a sleeve 147 interfitting with the chuck shaft 148.

The outer end of this shaft is recessed and spring 149 surrounds the recessed end 150 and abuts the shoulder on the shaft and the inner end of surrounding sleeve 147 adjacent the bearing block. The sleeve has an extension 151. The outer end of the chuck shaft has a collar 152 which is held on by means of nut 153 having threaded engagement with the threaded end of the shaft. Keyed to sleeve 147 is a pulley 154 which is driven by belt 155, as will be further explained below.

Surrounding collar 152 is a spider 156 having inwardly extending fingers adapted to engage the inner face of the collar and disengage the chuck from the flange on the web roll core. Spaced from the collar are two cam follower rollers 157 having threaded shafts 158 extending through holes (not numbered) in each of the two legs of the spider, said shafts being secured in position by means of nuts 159. Piston rod 160 connected to this spider passes through bearing plate 161 mounted on the outer side wall of the casing or vacuum chamber. The piston rod is attached to a piston (not shown) in fluid pressure-actuated cylinder 162 which is also fixed to said bearing plate. The fluid pressure-actuated cylinder 162 is of the double-acting type. Referring to FIGURE 5, the spring 149 normally urges the end of the chuck shaft 148 into abutment with the cylindrical flange 106; however, as an added safety measure and during the period when a core 99 is present, the cylinder 162 is subjected to fluid pressure in its head end; the piston rod 160 is thus held fully inward (in a chuck-to-flange 106 engaging direction). This does not mean that the rollers 157 continuously engage the outer face of collar 152; with the piston rod 160 thus held in its fully inward position, the spider 156 is preadjusted axially in respect to the piston rod 160 such that a clearance of $\frac{1}{16}$ to $\frac{1}{8}$ inch exists between the periphery of the rollers 157 and the outer face of collar 152. Thus, the spring 149 holds the chuck "in," but if the spring should fail, the chuck shaft 148 cannot move out by more than $\frac{1}{8}$ inch and a core will not fall out of a chuck.

The piston rod 160 is keyed, in respect to the walls, to avoid rotation of the spider; thus, the spider has its open sides disposed such that the collar 152 and chuck shaft 148 can pass through the spider when the yoke 144 is indexed. This cylinder is provided with suitable oper-

ating valve controls and with connections to a source of fluid pressure, e.g., a tank of compressed air.

On the inner side of each yoke 144 and fastened thereto are gears 163. These gears mesh with pinions 164 on the ends of horizontal drive shaft 165 journalled in suitable bearings 166 in side walls 139 and 140 of the inner sheath frame. Fixed to the shaft between the said walls are spaced sprockets 167 driven by chains 168 which likewise engage sprockets 169 keyed on shaft 170 journalled in bearings 171 in the side walls of the sheath frame. This shaft extends through a bearing 172 in a side wall of the casing.

In the central upper part of side walls 130 and 140 there are fixed stubshafts 173. Levers 174 are pivotally mounted on these stubshafts. The bottom ends of these levers contain bearings (not numbered) in which is journalled the shaft ends 175 of the large splicing roller 176 around which the web from the web rolls passes. Fixedly mounted in bearings 177 in the pivoted levers a short distance from the shaft ends of the roller is shaft 178 for an idler roller 179. Collars 180 are placed between the levers and the ends of the idler roller.

Belts 155 fitted on pulleys 154 for driving the web roll cores fit into small pulleys 181 keyed on shafts 182 extending through bearings 183 in the central part of the side walls of the casing. Keyed to these shafts outside the casing are pulleys 184 which are driven by belts 185 engaging pulleys 186 keyed to shafts 187 of driving electric motors 188 mounted on brackets 189 which are fastened to the casing.

Sheath frame 137 also supports a web-severing knife and attendant operating mechanism. This knife 190 (having a serrated edge) and mechanism as shown in FIGURES 2, 6, 18 and 19, is fixed between the ends of pivoted levers 191 keyed to shaft 192 journalled in bearings 193 fixed in side walls 139 and 140 of the sheath frame. Attached to one end of the shaft extending beyond a side wall is lever 194 having a pivot pin 195 interfitting with clevis 196 on the end of the piston rod 197 on fluid pressure-actuated cylinder 198. This cylinder is provided near its center with a pintle 199 which is journalled in suitable arms 200 on bracket 201 fastened to an outer side wall of the sheath frame. This cylinder is provided with valves, controls and connections to a source of fluid pressure whereby the knife can be actuated at the proper time.

The levers for the knife have about midway between the latter and the pivot point an integral lateral arm 202 having a curved slot 203. Stop bar 204 having its outer ends fixed to the side walls of the sheath frame, as shown in FIGURE 18 extends through this slot and coats therewith to limit the terminal position of the knife. A resilient (e.g., rubber) bumper 205 is fastened in the outer end of the curved slot 203.

Associated with this knife are two mechanisms which aid in severance of the web and in splicing of the severed trailing end from an exhausted core to the leading end of a new web roll. The first of these mechanisms is a means for moving the splicer roll and the web traveling around its surface against the new roll. This is accomplished by means of a fluid pressure-actuated cylinder 206 having an eye 207 on the outer end. Pin 208, affixed to bracket 209, extends through the eye and serves as a pivot point. The bracket, as shown in more detail on FIGURE 6, is attached to the center of upper crossplate 210 extending between and fixed to the sidewalls of the sheath frame. Piston rod 211 extending from a piston (not shown) in the cylinder has on its outer end a clevis 212 through which, and through lug 213 on lower crossplate 214, there extends a pivot pin 215. The ends of crossplate 214 are fastened to levers 174, which hold the shaft extending through splicing roll 176.

Referring to FIGURES 2, 6 and 7, a part of this mechanism for moving the splicing roll includes a cam follower roll 216 mounted on shaft 217 extending between

bearing brackets 218 mounted on arms 174 and protruding beyond its back edges. Cam 219 contacts with the follower roller. This cam is fixed to horizontal shaft 220 journaled in and extending between bearings 221 in the side walls 139 and 140 of the sheath frame. In FIGURE 7 there are shown on a larger scale details of the relation of this cam to the arm which moves the arm and splicer roll. Fixed on this shaft 220 is a pulley 222 carrying belt 223 which similarly engages a pulley 224 fixed on a parallel drive shaft 225 which extends through bearing 226 in said sheath frame. The ends of this shaft fit into coupling 227 in which is also fitted the drive shaft from combined motor and reducing gear box 228.

At the opposite end of shaft 225 is secured the rotor (not shown) of a switch 229; the stator (not shown) of the switch is secured to side wall 139. The switch is of the type described above. Each of its stationary contact members is connected to a corresponding stationary contact member in an identical switch (not shown) on the roll diameter measuring device. The two switches are suitably connected to a power source and thence to the motor in the combined motor and gear box 228, the whole being adapted to energize the motor and thus cause the shaft 225 and the rotor of the switch 229 to rotate until the rotor reaches an angular position corresponding to that of the switch on the roll diameter measuring device. In effect, this causes the cam 219 to assume a predetermined angular position in respect to the cam follower roll 216, thus the cam causes the lever 174 to swing the splicing roller 176 to a predetermined position such that, when the new web roll is later transported into the yoke 77, the periphery of new web roll will be just clear (about $\frac{1}{4}$ inch) of the splicer roll. The splicing roll must be so positioned for several reasons. The diameters of the new web rolls vary from roll-to-roll and the splicing roll, upon being driven by cylinder 206 for the purpose of making a splice, must come into splicing contact with the new web roll in a short known time increment and, further, must always close the $\frac{1}{4}$ inch gap, for different web rolls, in substantially the same known time increment regardless of roll size.

After a splice has been made, the cam and switch 229 automatically return to their starting position in anticipation of later accommodating a new roll. While the switch resets, the splicing roll and its support arms swing, by gravity and web tension, to a position such that a maximum gap exists between the splice roll and the web roll in anticipation of the installation of a new web roll in the web roll receiving chamber. During the period when the cam is driving the splicing roller 176 to a predetermined position, the cylinder 206 offers no restraint to the lever 174 since its associated valve means (not shown) causes the head end of the cylinder to be open to the atmosphere outside the vacuum chamber (the rod end is always open to the atmosphere).

The second of the two associated mechanisms is a lock bar assembly which is shown in greater detail in FIGURES 21, 22 and 29 (see also FIGURE 4). This assembly consists of a double U-shaped bracket 230 which is bolted to stop bar 204 near its center. The lower part of this bracket has arms 231 which extend around and are pivotally connected to plunger casing 232 by means of pins 233. Lock-lever 234 (rectangular cross-section) extends into this casing. The casing 232 has an internal profile formed by two parallel walls (shown in FIGURE 29) and two walls having parallel sections at either end joined by a tapered section at the center. The bottom end of this lever is connected by means of pin 235 to lug 236 on bracket 237 which in turn is fastened to cross-plate 214 which extends between levers 174.

In plunger casing 232 and surrounding the lock-lever is a spring 238 which abuts end plate 239 of said casing, and annular bearing cage 240 containing rollers 241 which contact with the tapered inner walls of the plunger casing and with the lock-lever 234. A plunger 242 con-

5 tacts the annular cage and is guided by means of collar 243 which is fastened to the casing by means of screws 244 or other suitable fastening means. The outer head of the plunger is curved to provide a cam surface. During the period when the roller 245 lies against the curved end of plunger 242, it depresses the plunger in respect to casing 232, in effect, driving the cage 240 and the two rollers 241 sufficiently far into the divergent part of the internally tapered portion of casing 232 that the lock-lever 234 cannot assume a locked position but is free to move axially in either direction. Roller 245 is normally in contact with the end of plunger 242 at all times except when the arm 246 starts to swing, the arm then being actuated at the same time that the shaft 192 starts to turn 10 to drive the knife. When roller 245 departs from the plunger, the spring 238 urges the cage 240 and the rollers 241 toward the convergent end of the taper thus effectively locking the lock-lever 234 and preventing it from moving in the same direction. The lock-lever 234 is 15 free, however to move toward the new web rolls; it does so when the splicer roll is moved into contact with a new web roll whereupon the lock-lever is snubbed or locked thus preventing the splicer roll from bouncing or being pulled away from the web roll due to normal tension 20 in the web or tension occasioned by the shock of cutting. The lock-lever then holds the splicer roll firmly in contact with the new web roll until such time as the splice has been accomplished and the knife has been withdrawn, whereupon the roller 245 again engages and 25 depresses plunger 242, in effect, releasing the splicer roll. This is accomplished by the turning of shaft 192 which actuates the knife. The arm 246 is fastened to block 247 which in turn is keyed or otherwise fastened to the knife-actuating shaft 192.

30 In the unwind unit, referring to FIGURES 2 and 6, it is desirable to lock the yokes into position at various times; for example, during normal winding and during web-severing operations. This is accomplished by means of a plate 248 fastened near the end of the yoke arm on the outside. A cup member 249 having a tapered recess 250 is welded or otherwise fastened to this plate. The tapered end 251 of piston rod extension 252 fits into the recess. The piston rod threadably engaged to the extension passes into fluid pressure-actuated cylinder 253 mounted in support member 254 in the side wall of the casing. The cylinder is provided with a piston, valves, controls and connections to a source of fluid pressure.

35 The large gears 163 fastened to yokes 144 are for the purpose of slowly rotating the yoke 180° from web-receiving position to web-feeding and core-removing position. During splicing and rotation of the yoke, however, the web is continuously unwound.

40 The core-removing chamber 70 is similar in construction to the web roll-receiving chamber 69, has a similar air removal opening and contains the same U-shaped arms and parts as in the latter, and for the sake of brevity the description and reference numbers will not be repeated. The outer doors 73 and 74 are similar in construction to the inner doors except that the doors are hinged on the side, rather than on the top. The operation of these doors will be described below in explaining the operation of the apparatus and controls.

The Coating Unit

45 The web (W) passes upwardly from central vacuum chamber into cupola 255 where it passes over web aligner roller 256 of an aligning device which keeps it in a predetermined path without restraint. The device consists of a pair of aligner rolls 256 and 257 which are rotatably mounted on shafts 258 and 259 which are supported in U-shaped frame 260; this frame is joined to and supported by a vertical shaft 261 which is rotatably carried in two bearings 262 mounted on a frame 263 which, in turn, is mounted to the upper face of the vacuum chamber 50. On the underside of the U-shaped frame is a

crossbar 264 carrying, at its center, a pin 265 engaged by a clevis 266 which is secured to the end of the piston rod 267 of the double-acting pneumatic cylinder 268. The head end of the cylinder is clevis mounted to a bracket 269 which is secured to the wall of the cupola 255. The edge aligning device further consists of a transducer 270 (Atcotran Edge Feeler; Control-Class 6172, Feeler-Class 6010A by Automatic Temperature Control Company) mounted to an inner wall of the cupola 255, which transducer has a sensing element 271 arranged to "feel" the position of one edge of the web W; additional elements comprise an electronic circuit means (not shown) connected to the transducer and to a four-way valve means (not shown) which valve is connected appropriately to the pneumatic cylinder 268 and to a source of air under pressure.

In operation, the web W passes up, out of the unwind unit, over-and-under aligner rolls 256 and 257, respectively, and thence over guide roller 272, the transducer continuously senses the position of one edge of the web and feeds a signal to the electronic circuit. When the web edge departs from a preselected path, air is admitted to one end of the pneumatic cylinder 268 by the valve means in response to a signal from the electronic circuit. The pneumatic cylinder then displaces the U-shaped frame and the aligner rolls 256 and 257 along a short arcuate path in one direction which, in effect, causes the web W to be displaced sidewise thus restoring the web W to the preselected path. The web then passes into elongated housing B, a horizontal vacuum-sealed passage, then over and under pairs of guide rollers 273—274 and then over roller 275 slightly downward into a lateral chamber 276 where it passes between power-driven feed rolls 277—278, then in a horizontal direction over guide roller 279 in vacuum coating chamber 280. Next, the web passes downwardly and around a pair of aligner rolls 281—282 similar to those above on the unwind unit which are supported, controlled and arranged substantially in an identical manner. The web then passes under and over guide rollers 283 then around guide rollers 284 and then the web passes over a small coating roll 285 beneath an extrusion hopper 286 where a coating composition (e.g., a light-sensitive gelatino silver halide emulsion, in the case of photographic film base) is extruded onto the surface of the web.

The coating composition can be fed to the hopper by means of pipe 287 leading from metering pump 288 connected to vessel 289 which in turn is connected by means of pipe 290 to a vacuum evaporating and concentrating apparatus 291.

Coated web W passes around a large roll 292, then upwardly past a guide roller 293 past heating platens 294 and into a vertical drying chamber provided with similar spaced heating platens 294 while guided by means of small guide rollers 295. This chamber is provided with a vapor removal opening 296 connected to duct 297 which is connected to a source of a suitable vacuum.

Joined to the drying chamber is a curved duct D which is vacuum-sealed and light-proof and provided with guide rollers 393 and, if desired, provided with heating platens 294, all like those in the heating chamber above the coating chamber.

A frame enclosure 298 is situated at the end of the curved duct D, directly above the rewind unit. Within this enclosure 298 is mounted a web aligning device similar to the edge aligning device hereinbefore described but, if desired, it can have only a single swiveled roll for guiding the web. Use of a single roll is advantageous for the reason that the web, at this point, carries a coating which cannot be permitted to touch a roll surface.

The Rewind Unit

Referring to FIGURES 9 through 14, the rewind unit like the unwind unit has three vacuum interlocked chambers, the inner one 300 of which comprises a vacuum

tight casing having a bottom 301, sidewalls 302 and 303, end walls 304 and 305, and an open top. The end walls are provided with door openings 306 and 307 which connect with core receiving chamber 308 and coated web roll removal chamber 309, respectively. The door openings have coacting sealing doors 310 and 311, respectively, which are identical in construction to and pivoted and provided with fluid pressure-actuated cylinder closing mechanisms like those in the unwind unit. For the sake of brevity these features of construction will not be repeated here.

The U-shaped arms for inserting the cores into the central vacuum chamber and for removing wound rolls of treated film from the central chamber are pivotally mounted and their gripping jaws operated by means of fluid pressure-actuated cylinders in the same manner as the comparable members in the unwind unit. The U-shaped notches and jaws are larger in size, however, because they grip the outer periphery of the cores directly, rather than the mandrels, as in the unwind unit. These cores 312 have an elongated cylindrical shell 313, end plates 314 having axial openings 315 which receive the end of a chuck to be described later.

With reference to FIGURE 9 of the drawing, it will be noticed that the endwalls of the central chamber are narrower at the bottom than at the top. By this construction the core receiving and web roll removal chambers can be made smaller.

Interfitting with the casing walls of the central chamber and spaced a short distance from the walls of the casing is a U-shaped frame 316. The bottom plate 317 of this frame rests on the bottom wall of the casing. The upper part of the frame has horizontal cross-plates 318 and 319 welded thereto to form a square top frame. Spaced brackets 320, welded to this frame and to the side walls of the U-shaped frame at upper end, give rigid support to this square frame.

In the central part of plates 318 and 319 and fastened thereto (e.g., by welding) are small bedplates 321 to which are welded vertical columns 322. These columns are reduced in diameter in their upper portions. In the center part of each column there is a vertical spindle 323 having its upper end threaded for engagement with a nut 324. Revolvably mounted on this spindle is a heavy support disk 325, a collar 326 and a retaining disk 327, the upper and lower outer surfaces of which are beveled or chamfered. The collar can be separate or integral with either disk. Between the nut and retaining disk is a washer 328. If desired, the support and retaining disks can be provided with suitable antifriction bearings.

A large flat gear plate 329 rests on the support disks and is held in operative position by means of the retaining disks. The bottom surface of the gear is flat and rests on the flat upper surface of the support disk. The upper surface has a beveled outer upper surface 330 which coacts with the beveled lower portion of the retaining disk. The vertical peripheral surface of the gear plate has gear teeth which intermesh with a pinion gear 331 in gear box 332 fastened to the square frame. Shaft 333 extends from this gear box through suitable bearings 334 and a seal (not shown) in the casing. Keyed to the shaft is an indexing crank 335, for turning the shaft and pinion gear and revolving the gear plate. On the upper surface of the gear plate, near the periphery, and spaced about 180° apart are two stop lugs 336. The outer edges of these lugs contact the outer surface of a similar stop lug 337 mounted on the top of the gear box. Near the lugs 336 and also fastened to the plates are small locking plates 338 having a key groove 339 into which interfit a plunger 340 actuated by a solenoid 341 that is also mounted on the gear box.

The gear plate has a large rectangular opening 342 through which the coated web W passes and which opening provides room for operation of certain of the web-controlling mechanisms. Referring to FIGURES 27-28,

a wrap-around roller mechanism is provided. Thus, attached to the bottom surface of the gear plate on opposite sides of the opening, there are brackets 343, the depending flanges 344 which have near their outer bottom ends bearings 345 in which are journalled shafts 346 having keyed to their outer ends sprockets 347. Keyed to the inner ends of these shafts are L-shaped levers 348 near the lateral ends of which there are provided two bearings 349 and 350. Parallel wrap-around rollers 351 and 352 extending between the levers have their shaft ends journalled in these bearings. One of the ends of each of these shafts has keyed thereto a pulley 353. The adjacent pulleys are driven in synchronism by interfitting belt 353'. The outermost roller 351 is driven by contact with the web. The opposite end of one shaft end has keyed thereto a pulley 354. Near the outer ends of the levers and extending from their back sides is a lateral arm 355 having bearings in which are journalled the shaft ends of another roller 356 which is parallel to roller 352 and also extends between the levers. On one end of this shaft is keyed a pulley 357. Belt 358 fits into the groove of this pulley and of pulley 355 so that all three rollers are driven in synchronism.

Depending flanges 344 also contain laterally extending stub shafts 359 on which are pivotally mounted the journal ends of arms 360 which constitute the sides of a pivoted knife frame. Knife 361 having a serrated edge extends across the ends of these arms and is fastened thereto by any suitable means, e.g., screws (not shown); a tucking bar 362 is fastened near the outer edge of the knife and to the arms.

Lateral extensions 363 extend backwardly near the center of arms 360 and a rod 364 extends between these lateral arms and is fastened thereto by means of nuts 365 which interfit with the threaded ends of the rod. The latter extends through the end of clevis 366 which is held in position on said rod by means of collars 367 fastened to the rod by means of set screws or other suitable fastening means. The other end of this member is fastened to the end of piston rod 368 extending from fluid pressure-actuated cylinder 369 having a suitable piston, valves, controls and connections to a source of fluid pressure.

Referring to FIGURES 9 and 10, a support post 370 is mounted on the gear plate near its periphery by means of bottom plate 371. Spaced vertical sides 372 of this post are fastened to this plate, and a flat plate 373 extends between and is fastened to the sides on their back edges near their upper ends. Lateral bracket 374, having a depending arm 375 on one end, has its other spaced depending arm fastened to the post. Bearing 376 in said arms 375 serves to support the pintles 377 extending laterally from near the center of fluid pressure-actuated cylinder 378. This cylinder contains the usual piston valves, controls and connections to a source of pressure. The piston rod 379 has a clevis 380 mounted on the outer end.

Referring to FIGURES 9 and 10, fastened to the front edges of sides 372 of the post is cross plate 384. Extending outwardly from the cross plate of this bracket are the bases 385 for spaced brackets 386 the ends of which have suitable bearings 387 that are adapted to receive a shaft 388 extending between said brackets. Levers 389 are pivotally mounted on the protruding ends of the shaft. In the other ends of the shaft, there are journalled the ends of a roller 390 which extends between the ends of the levers. One of the levers has a pivot pin 391 near its center and mounted on it is a clevis 390 and rod 379 whereby the lever and roller can be adjusted to a desired position.

Referring to FIGURES 9 and 12, on the edges of the side walls of the post there are fastened base plates 381 which support journal bearings 382 in which are journalled pintles 383 fastened to the cylinder 369 that actuates the knife.

Coated web W passes between levers 389 then around roller 390, contacts the outer roller 351 on the wrap-around roller mechanism and then passes around the core for the final roll of treated web. The core 312 is mounted on the central hubs 392 of chucks 393. The latter have shafts 394 mounted in bearing blocks in each end of centrally pivoted yokes 395. These chucks are spring-pressed in one direction and their operating means and their structure, etc., are essentially the same as those described in the unwind apparatus. The chucks on the unwind and rewind units are substantially the same but need not be identical; the unwind chuck shaft 148 (FIGURE 5) has a cylindrical recess 107 adapted to receive (axially) the tapered end 106 of mandrel 98, the mandrel 98 having been inserted into the end plates of core 99 while the core was outside the casing. No mandrel is used in the rewind unit and, therefore, the rewind chuck 393 has no recess, but has a short, projecting, shaft end having a short cylindrical section terminating in a truncated conical tip, both of which are concentric with the chuck axis. The shaft end engages the axial opening 315 in the end plates 314 of the core 312 (99). The shaft end is actually a part of shaft 394 and not a "hub 392." However, in order to eliminate unnecessary duplication, a detailed description of the operating parts for the chucks will not be repeated here.

Yokes 395 are each keyed to shaft 396 journalled in suitable bearing blocks 397 which are fixed to the sidewalls of the inner U-shaped frame. One end of the shaft also extends through a sidewall of the casing for the inner vacuum chamber where it is journalled in a bearing block 398 fixed to said casing and is connected to the driven shaft 399 of gear box 400 attached to the casing wall. Drive shaft 401 extends from the gear box and is driven in any suitable manner, e.g., from a controlled electric motor (not shown) whereby the yoke can be slowly revolved through 180° after removing a wound web roll and inserting a core.

Revolvably mounted on the drive shaft between the yokes and the walls of the U-shaped frame 316 are two pulleys 402 which are keyed together. Belt 403 fits into the groove of the inner of these pulleys and the groove of a pulley keyed to a chuck shaft journalled in the end of the yoke. The other pulley 402 is connected to driven pulleys 404 by means of belt 405. The latter pulleys are mounted on shafts 406 and 407 which are linked to suitable reversible drive motors 408 and 409 respectively by couplings 410. The motors are mounted on bases 411 attached to the casing in any suitable manner.

As shown in FIGURES 12 and 9, also attached to the top surface of gear plate 329 is a hollow square column 412 which holds a vertical fluid pressure-actuated cylinder 413, the depending piston rod 414 of which has attached thereto a rack 415. Attached to the under surface of the gear plate are two spaced depending brackets 416 through the ends of which passes shaft 417 having gear 418 (which meshes with the rack) keyed to it near its center, and sprockets 419 keyed near its ends. Chains 420 mesh with these sprockets and with sprockets 347 which pivot levers 348 and attendant wrap-around roll mechanism upon actuation of the piston and rack.

In the rewind unit it is also desirable to lock the yoke into position during normal winding and web-severing operations. This is accomplished by attaching to the end of the yoke a plate 421 having cup-shaped member 422 welded or otherwise affixed thereto. Into the tapered recess 423 of this member fits the tapered end 424 of rod 425 which extends through bearing 426 in the sidewall of the U-shaped frame. This piston rod extends into fluid pressure-actuated cylinder 427 extending through the sidewall of the casing and through a supporting plate 428 fastened to the casing. Core receiving chamber 308 and web roll removal chamber 309 of the rewind unit have door openings 429 and 430 which are

sealed with manually operated sealing doors 431 and 432 that are identical in construction with those in the unwind unit and for the sake of brevity a description of them is not repeated here.

Operation of the Apparatus

Before proceeding with a description of the various control mechanisms, alarms, electrical and fluid pressure systems, which of course can be modified in various ways, the general operation of the apparatus just described will be explained.

A brief discussion of the starting condition of the apparatus will probably lead to a better understanding of the invention. For example, to start the apparatus assume that a first roll of photographic film base is in the normal unwind position on the yoke, but the film has not been threaded through the machine; a second roll of film base is in the receiving chamber ready for loading into the unwind central chamber; a third roll of film base is available outside the apparatus; no spent cores are in the apparatus and the core removing chamber stands ready to receive a spent core from the unwind unit.

In general, the apparatus is always maintained in a state of readiness for the next cycle of events.

In the case of coating photographic film base, a first roll of such film base which has been mounted between the chucks 115 in the unwind apparatus is threaded around splicing roller 176, then under idler roller 179, and then upwardly out of the unwind unit and through the elongated housing B into the coating and drying unit C, through the elongated housing D and into and through the mechanism in the rewind unit E. The film base is unwinding from the first web roll located at the normal position of the yoke 144. A second full roll of film base has previously been placed manually into the grooves of the U-shaped arms in the web roll receiving chamber and its diameter has been measured. This roll of film base has its outer end fastened to the next convolution of film base by means of a wide piece of pressure-sensitive tape having areas of pressure-sensitive adhesive on both surfaces, the area of adhesive contact to the adjacent convolution being much less than the area attached to the leading end of the film and also much less than that on the opposite side of the double-faced pressure-sensitive tape. A suitable type of pressure-sensitive tape is shown in FIGURE 20 of the drawing in the position where the pressure-sensitive tape has been pulled away from the adjacent convolution of film base. The dotted circles represent areas of adhesive material on the under side of the tape and the sectioned area shows the area of adhesive on the other side of the tape. The adhesive area of the tape overlapping the end of the film base may be coextensive with the tape or in circular areas only, as may be desired.

The pivoted latch 104 is closed upon the mandrel of the second roll by the action of a fluid pressure cylinder, the outer door is closed, the chamber is evacuated, the inner door opened, and then the U-shaped lever is pivoted by means of another fluid pressure-actuated cylinder outside the casing. The outside diameter of this incoming second roll of film base has been measured by a suitable instrument which relays the information to a servo mechanism which rotates the cam 219 to position the splicing roller into such a position that it will be in close proximity to the surface of the incoming second roll of film base after it has been properly positioned between the chucks in the end of the yoke opposite the first, or running roll.

In placing the incoming second roll of film into splicing position the chucks on either end are allowed to push in by means of the actuating springs upon reversal of fluid pressure in the actuating cylinders. The latches are disengaged and the U-shaped levers are then pivoted backwardly to the original position in the vacuum roll

receiving chamber. During this entire operation of roll transfer the roll receiving chamber and the central chamber are evacuated. Upon return of the U-shaped levers the door is closed between the chambers. The vacuum in the web roll receiving chamber is relieved by admitting air, the outer door is opened, a third roll of film base is loaded into the U-shaped levers, the outer door is closed, the roll receiving chamber is evacuated and the inner door is opened; the U-shaped levers carrying the roll of film now stand in readiness to load the third roll into the yoke even though the previously loaded second roll has not yet been spliced in and, in fact, the running first roll may be only 10 to 20 percent expended. The U-shaped levers in the core removing chamber stand in the chamber in readiness to receive a core; the outer door has been closed, the chamber has been evacuated and the inner door is open.

After a period of time, the running first roll of film has nearly expired whereupon the new second roll (on the other end of the yoke) is accelerated to such a speed that the outer convolution is moving at the same speed as the other film traveling around the splicing roller. This is determined from combined electrical information obtained from a web velocity tachometer and the incoming roll diameter measuring device which combined information is fed to a controller associated with motor 188. This is accomplished as the first roll in the normal position is nearly completely unwound therefrom. When this first roll is essentially unwound, a signal is transmitted to a control center which activates an instrument that located the position of the splicing tape on the leading edge of the new second roll of film base.

As the pressure-sensitive splicing tape passes a predetermined position, the serrated knife 190 and the splicing roll 176 are actuated simultaneously by electronic means and by means of fluid pressure-actuating cylinders described above. The knife severs the trailing end of the nearly unwound first roll close to its core. As the film base is severed, the splicing roll swings which forces the trailing end of severed film base against the full second roll of film base in splicing position. While the serrated knife and splicing roll are actuated simultaneously, the splicing roll need only travel about $\frac{1}{4}$ inch as compared with about 15 inches for travel of the knife. The splicing roll comes into tangential contact with the new roll of film base and must be secured in position (e.g., by the mechanism shown in FIGURES 21, 22 and 29) against back-travel before any bounce occurs and before the knife severs the film base. The knife exerts considerable force on the film resulting in an instantaneous high tension which, without the securing mechanism could pull the splicing roll out of contact with the new roll of film base. The apparatus is controlled so that the trailing end and the splicing tape on the new second roll of film base pass the splicing roll at substantially the same instant so that a successful lap splice is accomplished "on the fly" and the film from the new second roll then proceeds along the normal web path with no interruption or disturbance in passage of the web into the coating and drying unit C and thence to and through the mechanism in the rewind unit E.

As soon as the splice has been made, the motor which has driven the new second roll of film base assumes a braking action to supply controlled tension to the film base as it is drawn into and through the coating unit; the few remaining convolutions of film on the unwound first roll remain on the core. The U-shaped arms in the core removing chamber are then actuated by a fluid pressure cylinder so that they pivot and move into the central vacuum chamber to grasp the first core mandrel of the exhausted first roll of web. The chucks holding this first core in the yoke are then retracted by means of fluid pressure-actuating cylinders and the first core of the roll is removed by said arms. The door between the chambers is closed, the vacuum is relieved, and the outer door

15

of the core receiving chamber is opened and the exhausted first core is manually removed from the said chamber; the outer door is then closed, the chamber is evacuated and the inner door is opened; the U-shaped arms now stand in readiness to be moved into the central chamber to receive the second core.

The yoke holding the second roll of film base is then slowly rotated 180° and thus the new second roll of film base is transferred from its splicing position to the normal running position. When it is in running position a new third roll of film base is introduced into the central chamber from the roll receiving chamber and deposited upon the yoke, whereupon the U-shaped levers return to the roll receiving chamber to be manually loaded with a fourth roll of film base in the manner previously described. The elements of the apparatus have now been restored to their starting positions except that the film is now threaded through the apparatus.

The film base is pulled through the elongated housing and into the coating and drying unit. As it passes into and through this unit it passes over and under the various guide support rollers and large roller as explained above. This coating chamber is likewise evacuated and a viscous solution, e.g., an aqueous gelatin silver halide emulsion, is extruded through the extrusion hopper onto the surface of the film base. The hopper can be raised slightly through a suitable mechanism as a splice approaches to allow the splice to pass between the hopper lips and the coating roll 285. As the film passes through the coating and drying unit and through the grooved, elongated housing D, which is also maintained under vacuum condition, it can be further heated, if necessary, and also inspected to determine if the coating is uniform and if there are any coating defects. Any vapors which are given off in the coating unit and in this housing are drawn off during the evacuation into suitable ducts or conduits connected with a vacuum pump.

The coated film base is guided over the various rollers as shown and then passes into the web aligning device in the cupola on top of the automatic rewind unit.

When it is desired to wind the coated film base with the coating on the outside, the coated film base is threaded around the roller 351, over roller 356 and then downwardly around the core at the bottom of yokes 395. The path of the film base is shown in a dotted line in FIGURE 1 of the drawing. This is the normal position of the core during a rewind operation. This core is inserted into the central chamber, initially, in essentially the same manner as rolls of film base are inserted in the unwind unit. The inner chamber is maintained under vacuum, the inner doors are closed except during roll or core transfer and the outer chambers evacuated with the outer doors closed before the transfer.

The upper end of the yoke contains an empty core which is fixed on the chucks so that it can be rotated. The coated film does not contact this core during rewind onto the lower core. Rewinding of the coated film continues until the rewound roll approaches its final diameter. At a signal from the control system the empty core is accelerated to the speed of the winding film. When the core surface velocity reaches the proper speed (web speed minus bias or wrap roll pull out film rate) the core drive system is changed from the speed match to a "soft motor" phase. At this stage, a signal starts the roll wrapping mechanism. Fluid pressure cylinder is actuated whereby the rack 415 and the pinion 418 cause chain 420 to rotate the levers 348 counterclockwise. The rolls 351 and 356 change the path of the coated film base so that it reverses and is wrapped around 270° or more clockwise around the new core. The new path is shown in a solid line.

At the end of the wrap roll orbit a signal switches out the bias (wrap roll pull out compensation). When the splice previously made in the unwind reaches the knife in the rewind, a signal from a film footage counter actuates the serrated cutting knife. This is accomplished by

16

means of the fluid pressure cylinder which pivots the arm supporting the knife clockwise to the cutting position. As the knife severs the film, preferably after passage of the splice so that the splice then lies on the outermost wrap of the full roll, it tucks the new leading end of the coated film between the new core and the wrapping roll 351 to start a new roll which rewinds in the roll-starting or upper position of the yoke.

At the end of the film-severing operation, a switch is actuated, furnishing a knife return signal which simultaneously changes the operation of the drive motor to a constant current for a winding operation, returns the wrapping rolls to the original standby position by again actuating the fluid pressure cylinder attached to the rack, and brakes the rotating, fully rewound roll of film to a halt.

The full, rewound roll of coated film base is then removed from the central chamber in the same manner as the cores are removed in the unwind unit. This is accomplished by previously pivoting the U-shaped arms into roll receiving position. The U-shaped roll transfer arms actually are not pivoted into roll receiving position after the roll reaches full size, but are pivoted inwardly immediately after yokes 395 are indexed 180°; the roll transfer arms thus stand in readiness to grip the roll core during essentially the entire winding period. After disengaging the drive motor chucks the wound roll is transferred from the central chamber into the roll removing chamber from which the roll is subsequently removed. A new core is then introduced into the now empty end of the yoke through the core-supplying chamber. To be more specific, as soon as the roll transfer arm has gripped a full roll and starts to move out, the empty core transfer arm also starts to move. Thus, as soon as the full roll is sufficiently clear of yoke 395, an empty core is deposited at the lower end of the yoke without delay. Immediately thereafter, the core transfer arm is withdrawn and the yoke is then indexed 180°. As described above, the roll transfer arms, having been suitably relieved of the full roll, are then moved into roll receiving position, adjacent to the yoke. After the new core is in proper position on the chucks and the inner door is closed, a new core is manually inserted into the core-receiving chamber and the outer door closed and this chamber evacuated and the inner door is opened.

The new core is now in driving engagement with the chucks connected to the drive motor, the yoke has been rotated through 180° to the roll starting position. At the same time the previously introduced core, which is now partially rewound and is continuously being rewound, is located at the normal winding position at the bottom of the vertical yoke.

When it is desired to wind the coated web with the coating surface on the inside, the gear plate 329 is rotated 180°. The film is then rethreaded onto the windup core. The direction of rotation of the drive motors for the chucks which drive these cores is automatically reversed.

A more detailed explanation of the operation of the device will now be given.

Splicing Control

Referring to FIGS. 32 and 33 a practical means for control of the splicing of the trailing end of an almost exhausted roll of film base (web) to the leading edge of a new roll of such base comprises a speed comparing device in which two pulse repetition frequencies which are each proportional to the velocity of two rotating elements are compared. In this FIG. 33, T-1 represents a tachometer which is operatively connected to the core 99 from which the film base W is unwinding. A pulse generator operatively connected to the tachometer (T-1) sends out 100 pulses for each revolution of the unwinding roll of web on said core. Tachometer (T-2) represents a second tachometer which is driven by the

feed rolls 277 or 278. One pulse is generated for each revolution of T-2. Associated with the tachometers and the pulse generators are a coincidence circuit and a counting circuit. The counter counts the number of pulses which are produced by T-1 during one revolution of T-2. The angular velocity of the core from which the web is unwinding obviously increases as the size of the roll decreases. Accordingly, the number of pulses generated by T-1 during one revolution of T-2 will also increase. When the pulses being produced during one revolution of T-2 reach a predetermined number, a signal will issue from the counter, preparing the apparatus for a splicing operation. A second signal sets the electrical control circuit in a "ready" condition for actuating the splicing mechanism. However, before this control circuit can become operative, it is necessary that the new roll be properly oriented for the splicing operation. This is effected by a magnetic pick-up (a suitable one being commercially available from Westinghouse Electric Corporation, Pittsburgh, Pa.), which is positioned adjacent the new roll. The new roll of film base, which has been brought up to speed, is spliced onto the trailing end of the exhausting roll when the magnetic pick-up sends a signal to operate a relay and the mechanism which controls the splicing roller and the cutting knife. (Signals are continuously emitted by the magnetic pick-up device; however, these signals are ineffective to operate the splicing mechanism until the control circuit, that is, the tachometers, pulsators and counting mechanism, have set the circuit in an operable condition.)

Rewind Control

After the splice is made at the unwind a footage-counting instrument which is independent of film speed is used to locate the splice and signal the mechanism for the knife for cutting the web in the rewind unit. Thus, it is possible to eliminate splices within the full base-roll (by locating the splice either at the beginning or end of the rewound roll) by removing in the rewind unit essentially the same length of web as is fed into the unwind unit. Rewind control functions are partially derived from the unwind system, and the end-of-roll detecting means. When the unwinding base roll diameter is several minutes from exhaustion, a signal (S-1 known as make-ready to wrap signal) is supplied to the rewind system. This signal initiates the following rewind operations:

(1) The empty core 312 in the upper end of the yoke is accelerated from rest to web speed match (roll peripheral velocity=web velocity) less a predetermined web velocity, which is equal to the average rate of web length introduced by the wraparound mechanism. (This value is referred to as bias and is necessary in order to eliminate a web scuff when the web first contacts the spinning core 312, as the rollers 351, 352 and 356 encircle it.) When speed match has been achieved, the motor drive measures the motor current at this speed, then removes the motor control from tachometer speed match and allows it to operate at this measured current value. (This step is known as the "soft-motor" phase, where the motor speed will easily follow a small increase or decrease of load applied to the core during the wrapping operation, without scuffing the web.) After the "soft motor" phase is achieved, a signal (e.g., S-1A) is originated in the motor drive system. This signal starts the wrap roll mechanism, which wraps the web around 270° of the empty core, and forms a cutting nip. Upon completion of the wrap roll orbit, this assembly activates a limit switch, which ceases its orbiting and also furnishes a signal (e.g., S-1B) whose function is to remove the speed match bias. The empty core motor continues to run as a "soft motor." (The finished roll windup motor has been winding film all this time in the normal constant current mode.) The rewind is now prepared to receive the web cutting knife signal, and divert the web from the lower full roll to upper empty core.

- (2) Upon completion of the knife operation in the unwind, a footage counter starts measuring web passed. When this footage equals the known web distance between unwind and rewind knives, the predetermined counter emits a signal (e.g., S-2).
- (3) Signal S-2 actuates the rewind web severing knife 362 which tucks the web end into the nip formed between the core and roller 356 of the wrap roll mechanism. The web then wraps on the upper core. At the end of the knife cutting stroke, a switch furnishes a signal (e.g., S-3) which simultaneously initiates the following operations:
- (A) Changes the mode of the drive motor for the upper core from "soft motor" to constant current (constant torque) for roll windup,
- (B) Returns the wrap roll mechanism to the original non-encircling position,
- (C) Changes the drive motor for the substantially complete wound roll from constant current to regenerative braking, then automatically to dynamic braking (so that the roll can be safely halted), and
- (D) Withdraws the knife.
- (4) Meanwhile, the web has continued to wind on the upper core 312 position, and the full roll of rewound coated film base must be removed and a new core placed in the chucks (lower position) before enough roll buildup occurs to cause interference between the upper roll and the wrap roll mechanism. The following operations occur, sequentially:
- (5) Upon braking of the full rewound roll to a stop, a completion signal is forwarded to an interlock relay (designated R-2). The full roll transfer arms are ready to grasp the rewound roll for removal, the second completion signal is furnished to interlock R-2, which will then allow the following sequence of events to occur:
- (A) The U-shaped full roll transfer arm latches 104 close,
- (B) The roll chucks 393 open,
- (C) The transfer arms remove the rewound roll from the yoke. (Completion of this also furnishes a signal to interlock relay R-3, to be covered later),
- (D) The roll removing chamber inner door (311) closes,
- (E) Roll chamber 309 air bleed valve opens, raising chamber pressure to atmosphere,
- (F1) Roll chamber outer door 432 "ready to open" signal is given, (2) Roll transfer latches open, (3) Outer door roll chamber "permissible open time" timer starts, (4) Operator manually opens the outer door, removes roll, closes door,
- (G1) An air bleed valve in the web roll removal chamber closes, (2) A completion of exhaustion signal is given to a vacuum interlock relay (R-5), (3) Central vacuum chamber line valve opens,
- (H) A differential pressure relay operates when the roll-chamber pressure equals the inner chamber pressure. This signal actuates the interlock relay which then permits the following operation:
- (I) Roll chamber vacuum valve closes,
- (J1) Roll chamber inner door opens, furnishing a signal for an interlock relay (R-6).
- (6) The placement of an empty core should occur almost simultaneously with full roll removal, to realize a small roll buildup on the upper core. When interlock relay R-3 senses that the full roll has been removed (see 5 C above), completion signal is furnished to interlock relay R-4. If a core is present in the core loading U-shaped transfer arms, a clearance signal is furnished to R-4, enabling the following core insertion sequence to continue:
- (A) The core latches close,
- (B) The U-shaped transfer arms introduce into the central chamber an empty core,
- (C) The core chucks close,
- (D) The latches open,

- (E) The U-shaped arms return,
  - (1) The yoke lock piston rod lock retracts,
  - (2) The yoke arm rotates 180°,
  - (3) The yoke arm piston rod locks the yoke in the new position,
    - (a) Completion signal is furnished to interlock relay R-6 (see 5J above) allowing the transfer arms to assume their normal position, in chamber 309,
- (F) Core receiving chamber inner door 310 closes,
- (G) Core receiving chamber air bleed valve opens,
- (H) When the core receiving chamber 431 reaches atmospheric pressure:
  - (1) Core chamber "ready to open" signal issues,
  - (2) Outer door core chamber "permissible open time" timer starts,
  - (3) Operator manually opens outer door, loads new core onto U-shaped transfer arms, closes door, and closing of door stops and resets the timer,
- (I) The core receiving chamber air bleed valve closes,
  - (1) The vacuum valve opens,
  - (2) A signal for completion of vacuum is furnished to interlock relay R-7,
- (J) When core receiving chamber pressure equals the pressure in inner chamber 300, a differential pressure relay supplies a signal to interlock relay R-7,
- (K) The latter relay then initiates the following events:
  - (1) A vacuum control valve for the core receiving chamber closes,
  - (2) The inner door opens,
    - (a) A signal is supplied to interlock relay R-3. This sets up the core introducing system for the next cycle.

As will be apparent to those skilled in the electrical control, pneumatic and vacuum control arts, various wiring diagrams, switches, micro-switches, timers, relays, vacuum control valves, etc., can be used to enable the apparatus to be controlled as described above without departing from the spirit and scope of the present invention.

The present invention is not limited to the coating of photographic film base with a photographic silver halide emulsion as described above. The apparatus is of general utility and can be used to coat various types of light-sensitive coating or light sensitive compositions onto film base to make photographic film. Thus, it can be used to coat gelatin sublayers, light-filter layers, anti-halation layers and antiabrasion layers onto a flexible hydrophobic film base or onto a layer on such a base.

The light-sensitive silver halide filter dyes, diazonium compounds, antihalation dyes or pigments, colloidal silver matting agents, etc., can be mixed with various water permeable colloids of synthetic or natural type, e.g., gelatin, agar-agar, albumin, cellulose derivatives, polyvinyl alcohol, polyacrylic and polymethacrylic acids and polyamides of acrylic and methacrylic acids, etc.

The invention is useful in coating paper webs and webs of other materials, e.g., polystyrene, polyethylene, polyesters of many types; rubber hydrochloride, etc.

It is not limited in its use to the coating of organic films and paper but can be used to coat metal foils with light-sensitive materials or foils containing layers of light-sensitive materials with other layers.

The apparatus is not limited to light-sensitive coatings as coating of various materials can be carried out in the apparatus. Examples of such materials in the coating of paramagnetic particles onto films to make magnetic recording films include ferromagnetic Fe_2O_3 and Fe_3O_4 , ferromagnetic chromium dioxide as described in Arthur Ser. No. 515,521, filed June 14, 1955, and complex oxides of manganese having the ilmenite structure as described in Toole U.S. 2,770,523, Swoboda Ser. No. 591,532, filed June 15, 1956, Swoboda Ser. No. 657,053, filed May 16, 1957 and Swoboda Ser. No. 657,052, filed May 6, 1957. A variety of binding materials and solvents therefor may

be used in preparing the magnetic dispersions including cellulose derivatives, vinyl polymers and other synthetic resins.

An advantage of this invention is that it provides a dependable and practical apparatus for continuously unwinding, splicing, coating and rewinding webs from separate rolls and onto separate cores. A further advantage is that the apparatus is compact and does not require separate large web accumulation chambers and attendant control devices.

An important further advantage of the invention is that the apparatus is completely automatic in operation, does not require continuous operator attention to the web during loading, coating and unloading. A still further advantage is the fact that the apparatus makes use of a process of sequential control which may be defined as a progressive automatic control system in which a succeeding operation is actuated by the completion of a previous operation. This permits compensating for any system lag occurring in earlier operations by automatically lengthening a cycle period so that a succeeding operation will not be initiated until the preceding operation has been completed. A still further advantage of the design is that many of the components, for example, drive motors, fluid pressure cylinders, solenoids, sensing devices and control units, are commercially available. From the above description still further advantages will be apparent to those skilled in the art.

What is claimed is:

1. An apparatus for the continuous treatment of a web at high speeds from separately introduced rolls of web and rewinding of the coated web into separate rolls which comprises, in series, an enclosed unwind unit, a passage between said unit and a coating unit and an enclosed rewind unit, the unwind unit comprising three adjacent chambers, the central chamber being provided with a rotatable yoke having means for holding driven web rolls, means in said chamber for severing the web on one of said rolls as it is unwinding and means for joining the leading end of the other while it is rotating at the same web speed, the other two chambers being a web roll receiving chamber and a core removal chamber, respectively, there being doors between said chambers and the central chamber, and in the outer walls of said other two chambers, means in said latter chambers for respectively transferring a roll of web into the central chamber and removing a web core from said chamber; said rewind unit also comprising three adjacent chambers, the central chamber being provided with a rotatable yoke for supporting driven roll cores, means for moving a web around a new core and means for severing the web as it is being wound on one of said cores while being carried around the new web roll core, the other two chambers being a web core supplying chamber and a web roll removal chamber, respectively, there being doors between said chambers and the central chamber and in the outer walls of said other two chambers, means in the latter chambers for respectively transferring a web roll core into the central chamber and for removing a roll of web from said chamber.
2. An apparatus for the continuous coating of web at high speeds and markedly reduced pressures from separately introduced rolls of web and rewinding of the coated webs into separate rolls which comprises, in series, an enclosed unwind unit, an enclosed passage between said unit and an enclosed coating unit, an enclosed passage between the coating unit and an enclosed rewind unit, means for evacuating each of said units and passages; the unwind unit comprising three vacuum interlock chambers, the central chamber being provided with a rotatable yoke for holding driven web rolls, means in said chamber for severing the web on one of said rolls as it is unwinding and means for joining the leading end of the other as it is rotating at the same web speed, the other two chambers being a web roll receiving cham-

ber and a core removal chamber, respectively, there being sealing doors between said chambers and the central chamber and in the outer walls of said other two chambers, pivoted arms in said latter chambers for respectively transferring a roll of web into the central chamber and removing a web core from said chamber; said rewind unit also comprising three vacuum interlock chambers, the central chamber being provided with a rotatable yoke for supporting driven web roll cores, means for carrying a moving web around a new core and means in said chamber for severing the web as it is being wound on one of said cores while being carried around the new web roll core, the other two chambers being a web core supplying chamber and a web roll removal chamber, respectively, there being sealing doors between said chambers and the central chamber and in the outer walls of said other two chambers, pivoted arms in said latter chambers for respectively transferring a web roll core into the central chamber and for removing a roll of web from said chamber.

3. An apparatus as defined in claim 2 provided with means for guiding the web from the central chamber of the unwind unit to the central chamber of the rewind unit.

4. An apparatus as defined in claim 2 provided with fluid pressure actuated cylinders for separately actuating the inner doors, means for transferring a roll of web and a web roll core, knives for severing the web, means for driving the cores and means for releasing the web cores from the yokes.

5. An apparatus as defined in claim 2 which is provided with means whereby the outer doors to the unwind and rewind units cannot be opened unless the inner doors are closed.

6. An apparatus as defined in claim 2 wherein the means for transferring a roll of web, removing a web core, transferring a web roll core and removing a roll of web, comprise pivoted arms having core-receiving ends and latches.

7. An apparatus according to claim 2 having means for recording and tracking the position of the spliced ends of the web as it passes through the apparatus, means for raising the coating unit as the spliced ends approach and pass said units, and means including a web footage counter for severing the web after the passage of the spliced ends as the web is being wound on a core.

8. An apparatus according to claim 2 having means for measuring the diameter of a new web roll and means for positioning the unwinding roll in close proximity to the new web roll to effect rapid splicing of the end of the former with the end of the latter.

9. An apparatus as defined in claim 1 provided with means for tucking the severed end of a web into a nip between a core and a squeeze roll.

10. An unwind unit for splicing rolls of web to form a continuous web comprising a casing providing a central vacuum chamber having side walls and end walls, pivoted sealing doors for closing openings in the end walls, said openings communicating with a vacuum interlock web roll receiving chamber and a vacuum interlock web core removal chamber, respectively, a pivoted arms in said latter chambers, respectively, for transferring a roll of web into the central chamber and removing a web core from said chamber, the central chamber containing an inner sheath frame in its upper part in which there are journaled bearings for a shaft carrying spaced yokes, the ends of which contain rotatable and slidable spring-biased chucks for supporting and rotating web roll cores, said sheath frame also supporting in its walls pivoted arms for a splicing roll, pivoted arms for a web severing knife, shafts for a mechanism to actuate said arms, shafts for means to rotate said yoke and slidable means for retracting said chucks.

11. An unwind unit as defined in claim 10 having

means for moving said splicing roll into proximity with a new web roll, and means for holding said splicing roll in contact with a web roll during splicing.

12. An unwind unit as defined in claim 10 having 5 means for moving said splicing roll into proximity with a new web roll, means for holding said splicing roll in contact with a web roll and means for measuring the web roll diameter of said new web roll and means actuated by said measuring means to position said splicing roll against the web roll during a splicing operation.

13. An unwind unit as defined in claim 10 provided with a fluid pressure actuated locking device for holding the yoke in the normal winding and splicing position.

14. An unwind unit as defined in claim 10 wherein the 15 casing is provided with motors for separately driving the chucks at the respective ends of the yokes.

15. An unwind unit as defined in claim 10 in which 20 there is provided a tachometer for determining the speed at which the web roll is rotating and a pulse generator connected thereto, a tachometer for determining the speed of the unwinding web and a pulse generator connected thereto, a coincidence circuit and a counting circuit associated with the tachometer and pulse generators so that when the pulses produced during one revolution of the 25 second tachometer reach a predetermined number, a splicing signal issues and a second signal issues when a new web roll is at the proper position and speed whereby the splicer roller is forced against the new web and the knife is actuated.

30 16. A web roll rewind unit for winding a continuous web into separate wound rolls comprising a casing providing a central vacuum chamber having side walls and end walls, pivoted sealing doors for closing openings in said end walls, said openings communicating with a vacuum 35 interlock web core receiving chamber and a vacuum interlock web roll removing chamber, respectively; the central chamber containing a U-shaped frame, the bottom and side walls of which closely interfit within said central chamber, and have journaled therein bearings for 40 a shaft carrying spaced yokes, the ends of which contain rotatable and slidable spring-biased chucks for supporting and rotating the web roll cores, said U-shaped frame also supporting a horizontal frame in the upper part of the central chamber, a plurality of spaced rollers on said 45 horizontal frame on which is mounted for rotation about a vertical axis, a horizontal plate, the bottom surface of this plate carrying a pivoted web wrap-around mechanism and a web severing knife and fluid pressure actuated means for operating the latter, said plate having a guide 50 roll near a central opening whereby the web can be passed through the opening in contact with said mechanism and onto the web cores, said U-shaped frame supporting in its walls the shaft for said yokes, drive shafts for rotating said chucks and slidable means for actuating said chucks.

55 17. A web rewind unit as defined in claim 16 having means for rotating said plate.

18. A web rewind unit as defined in claim 16 provided with a fluid pressure-actuated locking device for holding the yoke in the normal winding position.

60 19. A web rewind unit as defined in claim 16 wherein the casing is provided with motors for separately driving the chucks at the respective ends of the yokes.
